UNITED STATES PATENT OFFICE.

JAMES MADISON JACKSON, OF PARKERSBURG, WEST VIRGINIA.

SPRING-LUBRICATING DEVICE.

Application filed July 20, 1922. Serial No. 576,326.

To all whom it may concern:

Be it known that I, JAMES MADISON JACKSON, a citizen of the United States, and a resident of Parkersburg, in the county of 5 Wood and State of West Virginia, have made certain new and useful Improvements in Spring-Lubricating Devices, of which the following is a specification.

My invention relates to devices for lubricating vehicle leaf springs and similar articles and has for its object to provide a lubricant retaining material which may be readily, easily and economically wrapped or encircled about the entire spring or any 10 portion thereof so that dust, dirt and water may be prevented from retarding the resiliency thereof, and so that the spring may always be well lubricated.

Another object is to provide a flexible, 20 yieldable spring wrapping device of simple and cheap construction for the purpose of insuring constant lubrication of the spring.

Other objects of the invention will be apparent as the details of the invention are 25 disclosed and illustrated in the accompanying drawing forming a part of the application.

In the drawing:

Figure 1 is a side elevational view of an 30 elliptical vehicle spring showing the manner in which my invention may be applied;

Figure 2 is a cross sectional view of one type of my invention as applied to a leaf spring and secured thereto by means of nails;

Figure 3 is a fragmentary sectional view 35 of the device;

Figure 4 is a cross sectional view of a leaf spring provided with a modified form of the invention;

Fig. 5 shows a further modification whereby the absorbent and metal bands are stitched together to prevent slippage therebetween.

Figure 6 is a top plan view of a section of 40 spring equipped with one form of the invention, shown in section in Figure 5.

In carrying out my invention I provide a band of absorbent material of any desired width as indicated by numeral 5 in Fig. 3, having a center core or band of the same 45 width or less 6 composed of any soft flexible metal. This metal core while being of yieldable material still possesses sufficient strength to serve as a binding means for holding the absorbent material in its position upon the

spring and at the same time permits the 55 device to be wrapped around and snugly fit the irregular contour thereof.

While the metal core is sufficient of itself to retain the device in position on the spring, nevertheless, in order to prevent any possibility of displacement the overlapped ends 60 of the device as illustrated in Fig. 2, may be nailed or otherwise secured. The nails 7 will readily penetrate the soft metal core and upon contact with the hard metal spring 65 S will bend and clinch, thus sealing the device in position.

Figure 4 shows a modified form of wrapping the spring wherein I provide a band 70 of absorbent material 8 with an outer band 70 of soft metal 9 upon which at spaced intervals are arranged slots 10 and ears 11 capable of being depressed into the absorbent material as a means of clinching the device securely upon the spring. The slots 10 and 75 the openings caused by the depression of the ears 11 also provide means by which the absorbent material may be supplied with oil for the lubrication of the spring leaves.

One form of the invention is shown by Fig. 5 which shows a cross sectional view of a vehicle spring S with a spring wrapping comprising an absorbent strip against the spring and an outer strip of ductile metal and adapted to be stitched together as indicated at 12. The absorbent and metal strips should be stitched together before the device 80 is wrapped about the spring.

The bands of absorbent material and soft flexible metal may be applied with one or 90 more wrappings at right angles to the spring and may cover the entire spring or comprise only a single wrapping as shown by Fig. 1, wherein the upper part of the spring is shown wrapped with a series of 95 separate sections 15 any one of which may be replaced without disturbing the other sections. The lower left portion of the spring shows my invention indicated by numeral 16 wrapped spirally and at 17 is 100 shown a single wrapping of the device. Any manner of wrapping as illustrated may be employed to secure the best results under varying conditions. When the entire spring is covered the device should be wrapped 105 spirally and when only partly covered the device should encircle the spring once at right angles thereto with sufficient overlap.

ping of the ends to permit clinching or nailing if desired.

When a single section is applied to the lower half of the spring it will be unnecessary to anchor the device in any manner since any tendency to drift would be toward the thick portion of the spring which would thereby prevent slippage.

The absorbent material is provided so as 10 to retain the lubricating fluid for a considerable period so that whenever the motion of the vehicle causes the spring to flex or yield the pressure or friction upon the absorbent material will act to squeeze the 15 oil therefrom and thus to automatically lubricate the spring leaves. The openings provided in the device permit further lubrication of the spring and replenishment of the oil to the absorbent material whenever 20 desired.

While several modifications of the invention are shown in the drawing other arrangements for securing the device to the spring may be adopted or the invention may 25 be utilized for other purposes without departing from the spirit thereof. The metal band may be perforated as shown in Fig. 6 so that the absorbent material may be 30 stitched or laced thereto to form a rigid connection.

I claim:

1. A lubricating device of the character described adapted to be wound spirally about a vehicle spring and consisting of

35 spaced apart flat layers of absorbent material, and a soft or ductile layer of metal of approximately the same width as the absorbent layers and arranged between the same.

2. A lubricating device adapted to be wound 40 spirally about a vehicle spring and comprising a central soft or ductile metal plate flat in cross section and disposed intermediate absorbent plates or layers, and means holding the metal plate and absorbent layers together. 45

3. A spring cover comprising a flat strip of absorbent material, a flat strip of soft or ductile metal fitted against the absorbent strip, and ears projecting from the metal 50 strip into the absorbent strip for holding the strips together.

4. A spring lubricating device comprising flat strips of absorbent material and of soft or ductile metal approximately of the same 55 width and fitted face to face, means for securing the flat strips together, the metal plate being provided with perforations for the passage of securing means, the secured strips being adapted to be wrapped around 60 the vehicle spring or any portion thereof.

5. A vehicle leaf spring lubricating device of indefinite length adapted to be spirally wound about the spring and composed of absorbent and reinforcing layers of approximately equal width, and secured face to face. 65

JAMES MADISON JACKSON.
